UNITED STATES PATENT OFFICE.

CHARLES H. NORTON, OF PLAINVILLE, CONNECTICUT, ASSIGNOR TO NORTON COMPANY, OF WORCESTER, MASSACHUSETTS, A CORPORATION OF MASSACHUSETTS.

CYLINDRICAL-GRINDING MACHINE.

Application filed January 29, 1921, Serial No. 441,047. Renewed October 16, 1924.

To all whom it may concern:

Be it known that I, CHARLES H. NORTON, a citizen of the United States of America, residing at Plainville, in the county of Hartford and State of Connecticut, have invented certain new and useful Improvements in Cylindrical-Grinding Machines, of which the following is a full, clear, and exact specification.

10 My invention relates to a machine for grinding cylindrical objects and more particularly to a double head machine having driven work-supporting spindles adapted for the grinding of such articles as the pins and bearings of crankshafts.

15 The finishing of crankshaft pins and bearings, because of the high degree of accuracy and finish demanded, is now usually done on a grinding machine. In order to avoid torsional strains in the work during the grinding operation, it is advisable to drive the work positively from both ends, instead of having it driven from one end alone as in grinding straight cylindrical pieces.

20 When grinding the pins of crankshafts, it becomes necessary to support the shaft eccentrically of the axis of rotation of the driving spindles in special holding devices, this eccentricity varying with the throw of the crank. It is also highly important that the work be held rigidly and that the axes of the driving spindles be accurately aligned and maintained in such alignment for a long period of time, so that, when the work is fin-

25 ished, the axes of the pins will be parallel for pins angularly disposed relative to each other or in alignment for pins on the same side of the shaft. It will be apparent that any slight deviation from accurate alignment of the axes of the work driving spindles and any slight departure from the precisely synchronized drive for said spindles will result in imperfections in the work. Since the permissible error in this kind of work is very small, the elimination of such factors becomes highly important.

30 It is therefore one object of my invention to overcome these difficulties by providing a machine having a massive work-holding table of rigid construction in which the spindles of the work heads are supported on bearing surfaces rigid with the table so that their axes are aligned with each other and steadily held in such aligned relation, 35 and arranged in parallelism with the table

ways, whereby tables of different lengths may be readily interchanged for different grinding operations. To this end I provide a table having work head members rigid and integral with the table, said members having 40 aligning surfaces, which may be and preferably are V-shaped in cross section, adapted to receive bearing blocks having surfaces mating the aligning surfaces of said members, and spindle bearing surfaces which 45 may be partial cylindrical surfaces, the axes of which are in parallelism with the V-shaped surfaces, whereby the spindle axes will be in alignment. To hold the spindles in correct relation to the bearings, I may 50 provide adjustable bearing blocks and means for adjusting them with relation to the spindle.

55 It is a further object of my invention to provide efficient and positive driving connections from a shaft on the base of the machine to the two spindles in the work heads, whereby the balance of the spindles is assured and they are driven synchronously, providing 60 an even wear of the bearings and the elimination of torsional strain in the work during 65 the grinding operation.

70 It is a still further object of my invention to provide an oiling system in connection 75 with my spindle bearings that is highly efficient in operation and assures an even distribution and a constant supply of oil between the spindle and its cylindrical bearing member.

75 With these and other objects in view, as 80 will appear from the following disclosure, my invention resides in the combination of parts set forth in the specification and covered by the claims appended thereto.

85 In the drawings in which like reference 85 numerals indicate like parts:

Figure 1 is a front elevation of a grinding machine embodying my improvements, parts being shown in section or broken away to show the driving connections to the work 100 heads;

Fig. 2 is an enlarged transverse section through the left-hand work head, (Fig. 1), the table, and a part of the base;

Fig. 3 is an enlarged vertical section 105 through the work head and part of the driving connection thereto, a part of the spindle and its bearing block being shown in elevation;

Fig. 4 is a partial section through the gear 110.

casing on the end of the work head showing the chain drive;

Fig. 5 is a sectional detail of the mounting for the idler sprocket;

6 Fig. 6 is an enlarged perspective view of the work table, showing the integral work head members;

Fig. 7 is an enlarged perspective view showing a lower bearing block and its opposed adjustable blocks; and

10 Fig. 8 is a sectional view similar to Fig. 2 showing a modification of the spindle bearings.

In the embodiment of my invention selected for illustration, I have shown a slide, such as the work table 10, having parallel ways 11 mounted to slide on the parallel ways 12 of any suitable form of base 13, said slide or table being provided with 15 means for moving it on the ways, such as the usual rack 14 attached to the under side of the table and meshing with a pinion 15 on a transverse shaft 16 driven as from the hand wheel 17 through intermediate gearing 20 18. In Fig. 1 I have shown the grinding wheel W, which is mounted on a cross slide in the usual way, in operative relation to the work X.

The table 10, which has a massive rigid 30 construction, as will be apparent from an inspection of Fig. 6, is provided at its ends with rigidly and integrally formed work-supporting members 19 having surfaces 20 for receiving the bearing blocks 21, said surfaces being made in accurate axial alignment with each other, as by planing and scraping the parts, and arranged in parallelism with the table ways. These aligned surfaces thus form reference surfaces, both 35 initially and after the original bearing blocks become worn so as to require replacement, for accurately aligning the partial cylindrical surfaces 23 of said blocks and hence the axes of spindles 24 which are received in said blocks. The surfaces 20 are 40 preferably V-surfaces, as shown, the angle formed by the V being substantially a right angle. The V-shaped aligning surfaces are cut away in intermediate portions, as at the 45 points 25 and 26, to lessen the cost of scraping, it being noted that various shapes equivalent to that shown in the drawing may be known as V-shaped. The bearing blocks 21 having on their upper sides the 50 partial cylindrical surfaces 23 to receive the spindles are formed on their under sides with V-surfaces 27 mating the V-surfaces 20, so as to accurately fit the same. By 55 grinding or planing these blocks in pairs on an arbor, the V-surfaces 27 can be made to contact with the V-surfaces 20 at all 60 points not cut away, and the axes of the surfaces 23 will be accurately aligned, thus assuring the similar alignment of the work 65 spindles 24. The blocks may be drawn

tightly against the V-surfaces 20 by means of screws 30 (Fig. 2).

To hold the spindles in correct relation with the lower bearing blocks 21 and to prevent jumping or vibrating, I may employ 70 any suitable means, but I have shown a pair of upper bearing blocks 31 for each lower block, one of said upper blocks being arranged adjacent each end of the spindle. The upper sides of the spindles are enclosed 75 in partial cylindrical casings or caps 32 which are fastened to the work head members integrally formed with the table 10 by the screw bolts 33. The bearing blocks 31 are located between these casings and the 80 spindles and may be adjusted toward the spindles by means of screw bolts 34 provided with knurled heads 35 and the usual lock nuts 36. These screw bolts 34 form precision means for adjusting the bearing blocks 85 and their knurled heads are of such a size that the operator cannot manually set the bearing blocks against the spindles with sufficient pressure to crush out the oil film.

It is highly important in grinding the 90 pins of crankshafts, for example, that the work holders be accurately aligned when the work is clamped thereto to prevent any twisting or distortion of the shaft which would result in imperfections in the finished 95 work, and for a like reason it is important that the two work-driving spindles be driven in precise synchronism. I obtain such a drive by mounting a gear 37 on the outer end of each spindle 24 and driving 100 these gears by any suitable means such as from the shaft 38 which is mounted adjacent its ends in bearing brackets 41 connected to the table as by screws 42. To make the 105 machine self-contained, this shaft is preferably driven through a gear 43 arranged between its ends, said gear being splined thereto to allow relative sliding movement between it and the shaft, the shaft being supported on opposite sides of this gear by 110 a suitable bearing bracket 39 connected to the base. The drive shaft 44 mounted in the base of the machine (see Fig. 1) is in turn driven by any suitable means such as driving connections from a motor (not shown) on the back of the machine. These 115 gears are preferably sprocket gears driven by chains. The shaft 38 on the table is driven from a sprocket gear 45 on shaft 44 in the base by means of a chain 46 and the shaft 38 drives through sprocket gears 47 and chains 48 to the gears 37 on the work 120 spindles. I may employ idler sprockets 51 to take up any slack in the chains 48, the mounting for these idlers being clearly 125 shown in Figs. 4 and 5. I have shown the idler sprocket 51 (see Figs. 4 and 5) rotatably mounted on a stud 52 which is non-rotatably mounted in a rotatable bracket 54 as by a set screw 53, said bracket having a 130

large bearing surface engaging an end cap 55 which forms part of the housing for enclosing the gearing. A bolt 56 is keyed to this bracket and extends through a boss 57 on the end cap. The end of this bolt is formed with a reduced squared head to receive a wrench or other tool for rotating it, and, inwardly of this squared head, it is formed with a screw thread to receive a nut 58 thereon for drawing the bracket and cap in close frictional contact, whereby the idler will be held in adjusted position.

The spindles are provided at their inner ends with the usual plates 60 for fastening the work holders 61 to which the work X is clamped in the usual manner. To secure a fine rotary adjustment between the spindles 24 and the sprocket gears 37 for precisely aligning the work clamping means, I may mount at least one of the sprockets 37 in the manner shown in Figs. 3 and 4. I have there shown the sprocket 37 as being substantially cup-shaped to fit over the end of the spindle and connected thereto by bolts 62. The bolts extend through arcuate slots 63 in the sprocket to allow limited relative rotation between the sprocket and the spindle. On diametrically opposed sides of the sprocket I provide enlarged openings 64 having bevelled sides. These openings receive screw bolts 65 which screw into the ends of the spindle and have bevelled portions 66 thereon for cooperation with the bevelled sides of the openings 64. These bolts are both arranged at one side of a vertical plane passing through the axis of the spindle, while the centers of the openings 64 are arranged in this plane and both bolts are normally screwed down until their bevels engage the bevels of the openings. When it is desired to adjust the sprocket on the shaft, let us say in a clockwise direction, Fig. 4, the bolts 62 are loosened and the lower bolt 65 is likewise unscrewed so as to back off its bevelled surface from the bevelled surface in the opening 64, and by tightening the upper bolt 65 the sprocket is rotated by the engagement of the bevelled surfaces on the bolt and its cooperating opening until the bevelled surfaces on the lower bolt and its cooperating opening are again in engagement. To take up the end thrust, I provide the spindles 24 with collars 70 engaging the bearing blocks 21 at one end thereof and nuts 71 held in place by suitable lock nuts 72 at the opposite ends.

Another feature of my invention comprises an efficient oiling system which insures a copious supply of oil between the spindles and their bearing bushings. This may comprise an oil well 73 arranged at substantially the central portion of the work head below the work spindle and opening upward into the spindle bearings. I preferably convey the oil out of this well by

means of a chain 74 passing through slots 75 in the bearing blocks and around the spindles. Channels 80 are provided in the upper edges of the bearing blocks 21, these channels having their bottoms sloping away from the slots 75 to the ends of the bushings and towards the spindle so that as the oil is carried by the chain in the revolution of the spindle to the top of the spindle, some of it flows into these channels and along them in contact with the spindle, any surplus oil finding its way to the ends of the bushing where it drops by gravity or is thrown off by centrifugal force from the collars and the nuts 71 and 72 and is caught by the oil guards 76 and 77, from whence it is returned by gravity through the sloping channels 78 and 79 to the well 73.

An advantageous feature of my invention relates to the interchangeability of work tables. This is of considerable importance from the point of view of the user of such a machine having several different lengths of crankshafts to grind and yet not having sufficient of such work to warrant having two machines. The ways of the tables and the base being scraped to standard bars, it will be obvious that different tables will fit the same base and a user of this machine will be enabled to grind different lengths of work if equipped with a single machine having interchangeable tables of different lengths. For small differences in the lengths of the crankshafts, say several inches, it may be unnecessary to use different sized tables, such accommodation being obtained by substituting different work holders. Where the difference in length is greater, this method of adjusting the machine to the work would not be as desirable as the interchangeable tables.

In Fig. 8, I have shown a modified construction of the spindle bearings shown in Figs. 2 and 3, which may be advantageously employed in certain grinding operations, because it permits of a very fine lateral positioning of the spindle in its bearings. I there employ adjacent each end of a spindle two upper bearing blocks 81 similar to the bearing blocks 31 (Figs. 2, 3 and 7), these two blocks being preferably spaced from each other and from the lower bearing block 21, and arranged symmetrically on opposite sides of a vertical plane passing through the axis of the spindle 24 and at an angular distance of approximately 90° from each other. Each of these blocks, like the blocks 31, is provided with an adjusting screw 82 having a knurled head 83 and lock nut 84, the screws extending through the cap or casing 85, similar to the caps 32, except as shown modified in Fig. 8, to adapt it to receive two upper bearing blocks. My oiling system insures a copious supply of oil to the spindle and bearings, so that, during the normal

- operation of the machine, there always exists a thin film of oil between the spindle and the bearings in which it rests, which is only a fraction of a thousandth of an inch in thickness. Because of this fact, I am enabled to bring greater pressure to bear on the upper bearing blocks 81 arranged on one side of the spindle than on those arranged on the opposite side by a proper manipulation of the adjusting screws 82, and thus move the spindle in the direction of the greater thrust a fraction of a thousandth of an inch by forcing out some of the oil film between it and the bearing block 21 on that side of the spindle opposite the side receiving the greater thrust.
- It is obvious that changes may be made in the specific construction of my device and that equivalent elements may be substituted for the parts herein disclosed without departing from the scope of my invention as expressed in the claims appended hereto.
- Having thus described my invention, what I claim as new and desire to secure by Letters Patent is:
1. A double head grinding machine comprising a base having parallel ways thereon, a slideable work table having ways mating with the base ways, work head members integral with said table, spindle bearings thereon having bearing surfaces in precise axial alignment, and work-supporting spindles mounted on said surfaces and aligned thereby.
  2. A double head grinding machine comprising a base having parallel ways thereon, a work table slidably mounted on said ways, integral work head members on opposite ends of said table, lower spindle bearings thereon having cylindrical surfaces in accurate axial alignment, work-supporting spindles mounted on said surfaces and aligned thereby, and fine precision means to hold the spindles in correct relation with the lower bearing surfaces.
  3. A grinding machine comprising a base having parallel ways thereon, a slide movably mounted on said ways, spindle supporting members integral with the slide and having aligning V-surfaces and bearing blocks having V-surfaces mating with said aligning surfaces and rigidly fixed thereon, said blocks having spindle bearing surfaces axially parallel with said aligned surfaces of the slide.
  4. A grinding machine comprising a base having parallel ways thereon, a work table slidably mounted on said ways, a work head member integral with said table and having a V-surface arranged in parallelism with the table ways, a bearing block having a V-surface mating with the V-surface on said member, said bearing block having a cylindrical bearing surface axially parallel with and on the side opposite the V-surface there-
  - on, a work-supporting spindle mounted on said cylindrical bearing surface, and adjustable means for holding said spindle in correct relation with said bearing block.
  5. A double head grinding machine comprising a base having parallel ways thereon, a slideable work table having ways mating with the base ways, work head members integral with the table and having aligning V-surfaces parallel to the table ways, work supporting spindle blocks having lower V-surfaces mating with said aligning surfaces and upper cylindrical surfaces for the spindles, said blocks being rigidly mounted on said members, whereby the spindle axes traverse in a straight line.
  6. A double head grinding machine comprising a base having parallel ways thereon, a work table slidably mounted on said ways, lower bearing members rigidly fixed on said table in axial alignment and spaced relationship, spindles mounted in said bearings, supporting members rigidly fixed to said table and extending above said spindles, upper floating bearing blocks engaging said spindles, and means cooperating with said supporting members to position said floating bearing blocks accurately with relation to the spindles.
  7. A double head grinding machine comprising a base having parallel ways thereon, a work table slidably mounted on said ways and having work-supporting portions on its ends provided with V-shaped aligning surfaces, lower spindle bearing blocks having V-shaped surfaces mating with said aligned surfaces and rigidly mounted on said table portions, said bearing blocks having cylindrical surfaces in axial alignment, spindles mounted therein, and upper adjustable bearing blocks mounted on the table for engagement with the spindles to hold the same firmly against the cylindrical surfaces.
  8. A double head grinding machine comprising a base having a V-way and an associated way parallel thereto, a work table having ways on its under surface mating the ways on said base, said table having aligning V-surfaces adjacent its opposite ends parallel with said V-way, lower bearing blocks having V-surfaces mating with the V-surfaces of the table, said blocks being rigidly fastened to said table, each block having an upper cylindrical surface, the axis of which is parallel with the lower V-surfaces of the blocks, spindles mounted in said bearing blocks in axial alignment, a casing mounted over said spindles, adjustable upper bearing blocks mounted in said casing and means cooperating with said blocks and casing to hold the upper blocks in accurate contact with the spindles.
  9. A grinding machine comprising a slideable work table, work heads integral with said table, bearing surfaces in fixed axial

- alignment on said heads, work-driving spindles mounted in said bearing surfaces, a driving shaft extending longitudinally of the table, and chain driving connections between said shaft and the work-driving spindles. 70
10. A grinding machine comprising a base, ways on said base, a work table slidably mounted on said ways, rigid work heads arranged adjacent the ends of said table, bearing surfaces in fixed axial alignment on said work heads, work-driving spindles supported in said bearings, a shaft mounted on said slideable work table, chain driving connections between said shaft and the work-driving spindles, a fixed drive shaft in the base of the machine, and chain driving connections between said fixed shaft and the movable shaft. 75
15. A grinding machine comprising a base having ways, a work table slidably mounted on said ways, work head members rigid with said table, lower spindle-supporting blocks carried by said members and having cylindrical bearing surfaces, work driving and supporting spindles mounted on said surfaces, and means comprising finely adjustable bearing blocks arranged on opposite sides of a plane passing approximately 80 through the spindle axes to position and hold the spindles in proper relations with the supporting blocks and in precise alignment. 85
20. 11. A grinding machine comprising a base having ways, a slideable work table having ways mating the ways on the base, a spindle bearing block rigidly fixed on said table and axially parallel with the table ways, a work-supporting spindle mounted on said bearing block, driving means for said spindle arranged adjacent one end thereof and exerting a downward pull on the spindle, and a relatively massive work holder at the other end thereof, the pull exerted by said driving means and the weight of the work holder and work substantially balancing each other, whereby the bearing block will be evenly worn. 90
25. 12. A grinding machine comprising a base having ways, a work table slideable on said ways, work supporting heads integral with the table, V-shaped surfaces on the heads in precise alignment, lower bearing members having V-shaped surfaces mating with said surfaces on the heads, rigid connections between the heads and members, partial cylindrical surfaces on said members, spindles mounted on said members in fixed axial alignment and upper adjustable bearing blocks to hold the spindles in position relative to the members. 100
30. 13. A grinding machine comprising a base having standard parallel ways, a sliding work table forming one of a set which has ways mating with the standard base ways, work head members integral with said table, and work-supporting spindles mounted on said members in fixed axial alignment, whereby the table selected serves as a jig for supporting work of the particular size being treated. 105
35. 14. A grinding machine comprising a base, ways on said base, a work table slidably mounted on said base ways, work head members integral with and arranged adjacent the opposite ends of said table, lower spindle-supporting blocks thereon having cylindrical bearing surfaces normally in axial alignment, work-supporting spindles mounted on said surfaces, and means comprising finely adjustable bearing blocks to hold the spindles in proper relations with the supporting blocks and in precise alignment. 110
40. 15. A grinding machine comprising a base having ways, a work table slidably mounted on said ways, work head members integral with said table, a bearing block carried by said members and having cylindrical bearing surfaces, work driving and supporting spindles mounted on said surfaces, and means comprising finely adjustable bearing blocks arranged on opposite sides of a plane passing approximately 115 through the spindle axes to position and hold the spindles in proper relations with the supporting blocks and in precise alignment. 120
45. 16. A grinding machine comprising a base having parallel ways thereon, a work table slidably mounted on said ways, a work head member on said table which has a V surface arranged in parallelism with the table ways, a bearing block having a V surface mating with the V surface on said member, and a work supporting spindle mounted on said block. 125
50. 17. A grinding machine comprising a base having parallel ways thereon, a work table slidably mounted on said ways, a work head member integral with said table which has an upper V surface parallel with the table ways, a bearing block having a lower surface mating with said V surface and means for holding a work supporting spindle on said block. 130
55. 18. A grinding machine comprising a base having parallel ways thereon, a work table slidably mounted on said ways, a work head member integral with said table, a bearing block thereon, said member and bearing block having interfitting aligning surfaces parallel with said table ways, said bearing block having a cylindrical bearing surface axially parallel with said aligning surfaces, and a work supporting spindle mounted on said block. 135
60. 19. A grinding machine comprising a base, a work table on said base, two work heads mounted thereon, work driving spindles mounted on said heads in axial alignment, a driving shaft parallel with said spindles and driving connections from said shaft to each of the spindles, and means to synchronize the spindles. 140
65. 20. A grinding machine comprising a base, a work table slidably mounted on said base, two work heads mounted thereon, work driving spindles mounted on said heads in axial alignment, a driving shaft parallel with said spindles and driving connections from said shaft to each of the spindles, a driving member on each spindle, means connecting said shaft with each member to rotate. 145

tate the spindles, and means to rotate one spindle-driving member relative to the other to synchronize the spindles.

21. A grinding machine comprising a base, a work table slidably mounted on said base, two work heads mounted thereon, work driving spindles mounted on said heads in axial alignment, offset work holders on said spindles, a driving shaft parallel with said spindles, a gear mounted on each of said spindles, driving connections between said shaft and gears, and means to rotatively adjust one of said gears relative to the spindle to synchronize said work holders.
22. A grinding machine comprising a base, a work table slidably mounted on said base, two work heads mounted thereon, work driving spindles mounted on said heads in axial alignment, offset work holders on said spindles, a driving shaft parallel with said spindles, a gear mounted on each of said spindles, driving connections between said shaft and gears, means comprising screws having conical portions cooperating with conical apertures in one of said gears to rotatively adjust said gear relative to the spindle to synchronize the work holders.
23. A grinding machine comprising a support for the work, a work head member on

said support, a bearing block thereon, said member and bearing block having interfitting aligning surfaces parallel with said work axis, said bearing block having a cylindrical bearing surface axially parallel with said aligning surfaces, and a work supporting spindle mounted on said block.

24. A grinding machine comprising a support for the work, a work head member on said support which has a V surface arranged in parallelism with the axis of work, a bearing block having a lower V surface mating with the V surface on said member, and an upper partial cylindrical bearing surface and a work supporting spindle mounted on the upper bearing.

25. A grinding machine comprising a support for the work, spindle supporting members integral with the support and having aligning V-surfaces and bearing blocks having V-surfaces mating with said aligning surfaces and rigidly fixed thereon, said blocks having spindle bearing surfaces axially parallel with said aligned surfaces of the spindle supporting members.

Signed at Worcester, Massachusetts, this 28th day of Jan., 1921.

CHARLES H. NORTON.
